CLAIM

The ornamental design for a medical imaging apparatus, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of the medical imaging apparatus according to an embodiment of the present disclosure;

FIG. 2 is a back elevational view thereof;

FIG. 3 is a top plan view thereof;

FIG. 4 is a bottom plan view thereof;

FIG. 5 is a side elevational view of the right side thereof; FIG. 6 is a side elevational view of the left side thereof; and FIG. 7 is a perspective view taken generally from the upper, front, left-hand side thereof.

FIG. 8 is a front elevational view of the medical imaging apparatus according to another embodiment of the present disclosure;

FIG. 9 is a back elevational view thereof;

FIG. 10 is a top plan view thereof;

FIG. 11 is a bottom plan view thereof;

FIG. 12 is a side elevational view of the right side thereof; FIG. 13 is a side elevational view of the left side thereof; and,

FIG. 14 is a perspective view taken generally from the upper, front, left-hand side thereof.
